STOCKING

Martin J. Welch, Buffalo, N. Y.

Application August 26, 1946, Serial No. 692,957

1 Claim. (Cl. 2-239)

1

This invention relates to stockings made of sections which are of such shape that when sewed together they conform to the contour of the foot and leg.

It is the object of this invention to provide a stocking made of nylon, silk, rayon or similar materials knitted on a Tricot, Milanese or circular knitting machines in the piece and of the proper elasticity so as to insure a smooth fit and proper construction which will prevent runs in the fabric and in the finished stocking.

This application is related to an application for design patent filed by myself December 28, 1945, and serially numbered D-125,082.

In the accompanying drawings:

Fig. 1 is a side view of a finished stocking embodying this invention.

Fig. 2 is a top plan view of the same.

Fig. 3 is a bottom plan view of the same.

Fig. 4 is a fragmentary front elevation of the same.

Fig. 5 is a fragmentary rear elevation thereof.

Fig. 6 is a spread out view of the blank or section of the stocking forming the leg and the top of the foot of the completed stocking.

Fig. 7 is a similar view of the blank or section of the stocking which forms the underside or sandal of the foot and the heel portion of the stocking.

Fig. 8 is a plan view in a spread or open position of that section of the stocking which forms the welt.

Fig. 9 is a similar view of the welt section in a closed position.

In the following description the same reference characters indicate like parts in the several figures of the drawings.

The blank or section of the stocking shown in Fig. 6 and constituting the body of the same is made of sheet material and adapted to cover the thigh and the crus and the upperside of the instep of a human leg and comprises an upper leg panel 10 which is comparatively long and wide, a front or lower instep panel or flap 11 which is comparatively short and narrow and an intermediate tapering ankle panel or flap 12 which is arranged between said upper and lower panels and made integrally therewith, said intermediate ankle panel projecting forwardly from the lower end of said leg panel and said instep panel projecting forwardly from said ankle panel.

The widest central part of the upper panel 10 is provided with parallel longitudinal edges 14, the upper part of the same is somewhat wider

2

and provided with parallel longitudinal edges 15 which merge by downwardly converging edges 16 into the side edges 14 of this central part and the lower part of this upper panel has downwardly converging side edges 17. At its upper end the upper panel 10 terminates in a straight transverse edge 18 and at its lower end the same is provided with transverse shoulders 19 which extend inwardly a short distance from the lower ends of the inclined edges 17 of this panel. This upper panel is folded about a longitudinal axis and the corresponding longitudinal edges 14, 15, 16 and 17 are seamed or sewed together as shown at 20 in Figs. 3 and 5, so that this panel is of tubular form and adapted to enclose the crus and thigh of the leg.

The intermediate panel 12 is adapted to fit over the top of the ankle of the leg and the lower parts 21 of its longitudinal side edge are inclined and converge downwardly or forwardly relative to the length of this panel and the upper parts 22 of these side edges are parallel and connect with the transverse lower edges 19 of the upper panel so as to form a right angled notch between each 25 side edge part 22 and the corresponding transverse edge part 19, as shown in Fig. 6.

The lower panel 11 is adapted to fit over the instep of the foot and has its transverse front edge 23 curved convexly. The central parts 24 of 30 the opposite longitudinal side edges of the lower panel 11 are parallel and the lower ends of these side edge parts 24 are connected by lower inclined parts 25 with the opposite ends of the transverse front edge 23 and converge forwardly relative to the same. The upper ends of the parallel side edge parts 24 of the lower panel 11 are connected by upper or rear inclined parts 26 with the inner lower ends of the inclined edge parts 21 of the intermediate panel 12 and converge upwardly or rearwardly thereto so as to form V-shaped notches on opposite sides of the junction between the intermediate or ankle panel 12 and the lower or instep panel 11, as shown in Fig. 6.

The bottom of the foot consisting generally of the sole, heel, under or rear part of the ankle and the upper side of the toes are covered by a section having the form of a sandal or slipper which is constructed of sheet material as follows:

The blank of the sandal or slipper section comprises a central or sole panel 27 adapted to engage with the bottom of the foot, a lower toe panel 28 connected with the front end of the sole panel and adapted to engage with the underside 55 of the toes, an upper toe panel or flap 29 con-

nected with the front end of the lower toe panel and adapted to engage with the upper side of the toes, a front heel panel 30 connected with the rear end of the sole panel and adapted to engage the front part of the heel, a rear heel panel 31 connected with the rear end of the front heel panel and adapted to engage with the rear part of the heel, and a rear ankle panel or flap 32 connected with the rear end of the rear heel panel and adapted to engage with the under side or nape of the ankle in rear of the heel, these panels being formed integrally from a sheet of suitable material.

The sole panel is provided on its opposite sides with parallel longitudinal edges 33 the opposite side parts of the lower toe panel 28 are made, respectively, of substantially V-shape, the summit 34 of each of these V-shaped parts being connected by an inclined edge 35 with the front end of the longitudinal edge 33 on the corresponding side of the sole panel so that these inclined edges 35 converge rearwardly and the rear part of the lower toe panel tapers rearwardly. The longitudinal opposite sides of the front part of the lower toe panel 28 are also provided with inclined edges 36 which converge forwardly from the summits 34 so that this part of the lower toe panel is of forwardly tapering form. The longitudinal opposite sides of the upper toe panel 29 are provided with inclined edges 37 which diverge from the front ends of the inclined front edges 36 of the lower toe panel so that this upper toe panel is of tapering form. At its outer extremity the upper toe panel is provided with a transverse edge 38 which is curved concavely.

The opposite side parts of the front heel panel 30 are made, respectively, of substantially V-shape, the summit 39 of each of these V-shaped parts being connected by an inclined edge 40 with the rear end of the longitudinal edge 33 on the corresponding side of the sole panel so that these inclined edges 40 converge forwardly and the front part of the front heel panel tapers forwardly. The opposite longitudinal sides of the front heel panel are also provided with inclined edges 41 which converge rearwardly from the summits 39 so that the rear part of the front heel panel tapers rearwardly.

The opposite side parts of the rear heel panel 31 are also made, respectively, of substantially V-shape, the summit 42 of each of these V-shaped parts being connected by an inclined edge 43 with the rear end of the inclined edge 41 of the companion front heel panel so that the front part of the rear heel panel is of forwardly tapering form. The opposite longitudinal sides of the rear heel panel are also provided with inclined edges 44 which converge rearwardly from the summits 42 so that the rear part of the rear heel panel tapers rearwardly.

The ankle panel 32 is comparatively narrow and provided with opposite parallel longitudinal edges 45 which connect at their front ends with the ends of the inclined rear edges 44 of the rear heel panel and connect at their rear ends with opposite ends of the transverse edge 46 of the ankle panel.

Preparatory to assembling this sandal with the body of the stocking, the sandal blank is sewed up into the shape of a sandal or slipper which will engage the underside of the foot and enclose the heel and toe of a human foot. This is accomplished in part by seaming or sewing together the inclined edges 41 on opposite sides of the rear part of the front heel panel with the inclined

edges 43 on the front part of the rear heel panel, as shown at 47 in Figs. 1 and 3 thereby closing the notches 58 on opposite sides of the sandal blank between the respective inclined edges 41, 5 43 of the front and rear heel panels, an upwardly opening pocket on the sandal section which is adapted to receive the heel of the human foot.

In a further operation the upper toe panel 29 is turned rearwardly over the lower toe panel 10 28 along the transversely folding line 48 between the same and the inclined side edges 37 of the upper toe panel are sewed or seamed to the inclined side edges 36 of the lower toe panel by stitches 49, as shown in Figs. 1, 2 and 4, thereby forming a rearwardly opening pocket which is adapted to receive the toes of a human foot. As the front and rear heel panels are sewed together and the lower and upper toe panels are sewed together in the manner described the inclined 15 side edges 35 of the lower toe panel, the parallel side edges 33 of the sole panel, the inclined side edges 40 of the front heel panel, the inclined side edges 41 of the rear heel panel and the parallel side edges 45 of the ankle panel are raised so as to in effect produce an upwardly opening trough 20 which receives the lower part of the human foot and form side walls which engage opposite sides of the arch, heel and ankle of the foot. The several edges of the lower toe panel, sole panel, 30 front and rear heel panel and ankle panel are connected, respectively, by longitudinal seams or sewing stitches 50, with the inclined front side edges 25 of the instep panel, the parallel side edges 24 of the instep panel, the inclined rear side edges 26 of the instep panel, the inclined edges 21 of the ankle panel and the parallel side edges 21 of the ankle panel. As shown at 51 in Figs. 1, 2 and 4 the front transverse edge 23 of the instep panel is also stitched or seamed to the rear edge 40 38 of the upper toe panel and, as shown at 52 in Figs. 1 and 3, the rear transverse edge 46 of the ankle panel is connected with the transverse edges 19 on the lower edge of the leg panel.

The tubular body of the stocking is usually 45 finished by an annular welt or band which may be formed of a rectangular sheet blank 53 which is doubled by folding the same lengthwise on a line 54 midway between the longitudinal edges of this blank, and thereafter seaming together the 50 transverse edges 55 of the two layers, sewing the lower turned edge of this welt by stitches 56 to the upper edge 18 of the leg panel and finishing the upper edges of the two plies of the welt in the manner of picot, as shown at 57, in Figs. 1, 55 2, 3 and 9.

Although the several sections or parts of this stocking may be made of any suitable material the same are preferably made of a knitted material, which has the proper elasticity to insure a 60 smooth fit of the stocking on the human leg and which also is of such construction that the same will not run and still present a neat and finished appearance.

The leg portion of this stocking is preferably 65 made of a material having a weight corresponding to sheer, chiffon or service and the welt and sandal are preferably made of similar fabric in order to blend with the leg section, but preferably of heavier and more durable weight.

It will be noted that in this stocking no seams are present on the bottom of the foot section thereby avoiding the discomfort experienced by wearers of stockings as heretofore manufactured 70 75 having seams along the bottom of the foot.

I claim as my invention:

A stocking comprising an upper section and a lower section, said upper section being constructed from a sheet blank having an upper leg panel, a front instep panel and an intermediate ankle panel connecting the front part of the lower end of said leg panel with the rear edge of the instep panel and this upper leg panel being folded cross-wise so as to engage its opposite longitudinal edges and connecting the same to form a tube adapted to receive a human leg and the lower rear part of said leg panel having transverse edge portions adjacent to its longitudinal edges, said intermediate and front panels adapted to extend forwardly over the ankle and instep of a human foot and said instep panel having parallel side edges and said ankle panel having V-notches on its opposite side edges and said lower section being constructed from a sheet blank to form a central contracted sole panel having parallel side edges and adapted to engage the sole of the foot, an enlarged under toe panel extending forwardly from the sole panel and adapted to engage the underside of the toes, an enlarged over toe panel extending upwardly and rearwardly from the front edge of the under toe panel and adapted to engage the upper side of the toes, an enlarged front heel panel extending rearwardly from the sole panel and adapted to engage the front part of the heel, a rear enlarged 30

heel panel extending rearwardly from the front heel panel and adapted to engage with the rear part of the heel, and a narrowed ankle panel extending rearwardly from the rear heel panel and adapted to engage the ankle back of the heel and having a transverse rear edge, said front and rear heel panels being connected to form a pocket for receiving the heel, said lower and upper toe panels being connected to form a pocket for receiving the toes, and said upper and lower sections being connected along the opposing longitudinal edges of the instep and sole panels, also along the opposing transverse edges of the instep and upper toe panels, and also along the transverse edge portions between the lower part of the leg panel and the rear end of the ankle panel to form a continuous lower edge in the rear part of this tubular leg.
